UNITED STATES PATENT OFFICE

PAUL R. PUCKETT, OF ATLANTA, GEORGIA, ASSIGNOR TO CHASE COMPANIES INC., OF WATERBURY, CONNECTICUT, A CORPORATION

PORTABLE ELECTRIC HAND LAMP

Application filed September 21, 1927. Serial No. 220,900.

My invention relates to an improvement in portable electric hand-lamps, popularly called "flashlights," the object being to produce, at a low cost for manufacture, a simple, compact, durable and convenient lamp of the character described, constructed with particular reference to ease of manufacture and reliability in use.

With these ends in view, my invention consists in a portable electric hand-lamp characterized by a plate-like disk-shaped switch-member located in a plane at a right angle to its axis and held in place by its periphery.

My invention further consists in a lamp characterized as above and having its switch-member provided with an outwardly-projecting finger-piece, by which it is operated.

My invention further consists in a lamp characterized as above and having means for applying variable friction-restraint to the movement of its disk-shaped switch-member.

My invention further consists in a lamp characterized as above and having certain other details of construction and combinations of parts as will be hereinafter particularly pointed out in the claims.

In the accompanying drawings:

Fig. 1 is a view in side elevation of one form which a portable electric hand-lamp embodying my invention may assume;

Fig. 2 is a plan view of the outer or forward end thereof;

Fig. 3 is a broken enlarged view thereof in longitudinal section on the line 3—3 of Fig. 1;

Fig. 4 is a view thereof in transverse section on the line 4—4 of Fig. 3;

Fig. 5 is a detached perspective view of the switch-member;

Fig. 6 is a similar view of the insulating-ring;

Fig. 7 is a sectional view thereof on the line 7—7 of Fig. 6;

Fig. 8 is a broken view in elevation of the upper or forward end of one of the modified forms which my improved lamp may assume;

Fig. 9 is an enlarged longitudinal sectional view thereof on the line 9—9 of Fig. 8;

Fig. 10 is a broken, detached, perspective

view of the switch-member of the structures of Figs. 8 and 9; and

Fig. 11 is a detached view in longitudinal section of one of the modified forms which the cap of my improved lamp may assume.

In the particular embodiment of my invention chosen for illustration and shown in Figs. 1 to 7 inclusive of the drawings, I employ a plate-like disk-shaped switch-member 15 arranged at a right angle to the major axis of the lamp and interposed between the inwardly-turned bearing-flange 16 at the outer or forward end of the tubular casing 17 and the inner edge of an insulating-ring 18 of fibrous material located within and secured to the cap 19 of the lamp by means of indents 20 therein, whereby the switch-member is positioned and movably held in place by its periphery, rather than by pivots. The said cap 19 is formed with the usual threaded skirt 21, adapting it to be screwed over the enlarged, threaded outer or forward end 22 of the casing 17. The upper edge of the cap is turned inwardly to form a retaining-flange 23 which engages with the usual plano-convex lens 24, the edge of the inner face of which rests upon the outer edge of the insulating-ring 18 aforesaid.

The plate-like disk-shaped switch-member 15 is formed upon one side with a finger-piece 25 extending outwardly through a slot 26 in the cap 19, this finger-piece providing for the oscillation of the switch, as well as for the convenient suspension of the lamp as occasion may require. The said finger-piece also constitutes an anti-rolling device for the lamp.

At a point substantially opposite the finger-piece 25, the switch-member is furnished with a contact-pin 27, adapted, when the said switch-member is turned in one direction, to engage with a contact-finger 28 formed upon the inner end of a conductor-plate 29 applied to the inner face of the insulating-ring 18, to which it is clamped by an outwardly-turned finger 30 formed integral with it. The outer end of the conductor-plate 29 aforesaid is in electrical engagement with the periphery of the outer end of a conical reflector 31, the inner end of which is formed

with a threaded socket-sleeve 32, which receives and mounts the threaded base or stem 33 of an incandescent electric lamp-bulb 34 of any approved type. The socket-sleeve 32 of the reflector 31 is axially in line with a concentric guard-opening 35 formed in the switch-member 15, which, in the embodiment of my invention under consideration, is struck downwardly to form a concentric guard-cone 36, the several purposes of which will be hereinafter set forth.

The center-contact 37 of the incandescent electric lamp-bulb 34 engages, as is usual, with the positive electrode 38 of the adjacent 15 electro-chemical cell 39 within the casing 17. The cell 39 rests upon a corresponding cell 40, which, in turn, rests upon a spiral spring 41 located in the bottom of the casing 17 and exerting a constant effort to maintain the electrode 38 in engagement with the center-contact 37. Furthermore, the spring 41 electrically connects the bottom of the cell 40 with the casing 17.

As thus organized, the switch-member 15 25 virtually divides the interior of the lamp into a cell-chamber 42 and a lamp-chamber 43, so that, in case of the disintegration of the electro-chemical cells, any efflorescence of material thereof will be practically prevented 30 from working its way into the lamp-chamber 43 and corroding the reflector and the contacts 27 and 28 and otherwise fouling the parts in the cap, which would otherwise have to be carefully disassembled and cleaned before the introduction of fresh electro-chemical 35 cells.

On account of the interposition of the switch-member between the flange 16 of the casing 17 and the inner edge of the insulating ring 18 carried by the cap 19, it will be understood that, by turning the cap one way or the other with reference to the casing, the amount of frictional restraint imposed upon the oscillation of the switch-member by its finger-piece 25 may be varied as desired, or this restraint may be made so great that the switch-member will be locked in any chosen position.

It will be apparent from reference to Figs. 1 and 4, that while the lamp is grasped in its middle portion by the hand, its switch-member 15 may be easily operated for turning the light on or off by moving the contact-pin 27 into and out of engagement with the contact-finger 28, the current flowing as is usual in lamps of this class.

As shown herein, the switch-member 15 is self-centering, since, on account of its form, it will center itself within the cap 19 with respect to the axis of the lamp, without assistance on the part of the assembler and without the employment of any fastening means after its finger-piece 25 has been passed through the slot 26 in the cap, which at this time is held open side up.

The switch-member 15 also has a highly important guard function, as will now be described. In assembling my improved hand-lamp, the base 33 of the lamp-bulb is screwed into the sleeve-socket 32 of the reflector 31, 70 which is then inserted into the insulating-ring 18 of the cap 19. The finger-piece 25 of the switch-member 15 is then passed through the slot 26 of the cap from the interior thereof, after which it is brought to rest upon the inner edge of the ring 18. The cap, with the several parts thus assembled within it, is now ready for application to the casing 17. This must be done against the counterurge of the spiral spring 41 in the bottom of the casing, 75 exerting its effort through the electro-chemical cells. Now, in case the center-contact 37 of the bulb is not brought into linear registration with the electrode 38, the tendency will be to cant the bulb 34 and with it the reflector 31 within the cap 19. The degree of such canting is kept within such limits, by the guard action of the guard-opening 35 in the reflector 31, that jamming is avoided and the power of the spring 41 utilized to bring 80 the lamp and reflector into line with the major axis of the lamp when the cap is finally screwed home on the casing.

In addition to the function of the switch-member 15 in guarding the lamp-bulb and 85 the reflector against undue canting, as above described, it performs, as shown in Figs. 1 to 7 inclusive, another highly important guarding function in limiting the outward movement of the cells, whereby they are prevented 90 from becoming short-circuited and thus exhausted, in case of accident, as well as in guarding against the breakage of the lamp-bulb under certain conditions.

In case the lamp-bulb should, as not infrequently happens, unscrew and move outward, the electrode 38 of the cell 39 would ordinarily, under the urge of the spring 41, move into engagement with the threaded socket-sleeve 32 of the reflector 31, and thus short-circuit the cells, which would result in their 105 speedy exhaustion. Under my improvement, such a result is guarded against by the inner end of the guard-cone 36, which will be engaged by the outer face of the cell 39, and the outward movement thereof, under the urge of the spring 41, positively stopped before its electrode 38 can engage with the edge of the socket-sleeve 32, as described.

The guard-cone 36 also, by positively limiting the outward movement of the cell 39, as just above described, prevents the same from pushing the glass of the bulb 34 against the inner face of the lens 24, resulting in the destruction of the lamp-bulb.

In Figs. 8, 9 and 10, I have shown a modified form of my plate-like switch-member, which corresponds in form and function to the switch-member 15, but instead of being oscillated around its axis for the purpose of 130

making and breaking the circuit, it is adapted to be flexed at a right angle to its plane for that purpose. With this end in view, its central portion is formed on either side of its finger-piece 25 with semi-circular cuts 44 intersected by radial cuts 45 in line with the opposite edges of its said finger-piece, whereby the central portion of the switch-member, including its conical portion 36, may be flexed 10 with respect to its plane on the tongue 46 lying between the inner ends of the semi-circular cuts 44. An upward thrust on the finger-piece 25 brings its conical portion 36 into contact with the reflector 31 at the point 47 (Fig. 9).

In the modified form shown by Fig. 11, the lamp is provided with a suspension bail 48, the ends of which are turned inwardly through the cap 19 and insulating-ring 18, 20 holding the latter in place in the cap.

I claim:

1. A portable electric hand-lamp, having a casing, an electro-chemical cell, a lamp-bulb in the circuit thereof, and a peripherally-mounted plate-like disk-shaped switch-member interposed in the said circuit for making and breaking the same, located in a plane transverse to the axis of the lamp and formed with a guard-opening receiving the 30 stem of the lamp-bulb and guarding the same against canting in assembling the lamp.

2. A portable electric hand-lamp, having a casing, a cap therefor, an electro-chemical cell in the casing, a lamp-bulb in the said 35 cap, an insulating-ring in the cap, and a plate-like switch-member interposed between the upper edge of the casing and the lower edge of the said ring in a plane transverse to the axis of the lamp and movable for 40 making and breaking the circuit of the said cell through the lamp-bulb.

3. A portable electric hand-lamp, having a casing, a cap therefor, an electro-chemical cell in the casing, a lamp-bulb in the cap, 45 an oscillatable plate-like switch-member located in the cap in a plane transverse to the axis of the lamp-structure, an insulating-ring in the cap, contacts carried by the said ring and switch-member, and means for oscillating the latter to engage and disengage the contacts for making and breaking the circuit through the cell and bulb.

4. A portable electric hand-lamp, having a casing, a cap therefor, an electro-chemical 55 cell in the casing, a lamp-bulb in the cap, an oscillatable plate-like switch-member located in the cap in a plane transverse to the axis of the lamp-structure, an insulating-ring in the cap, contacts carried by the said 60 ring and switch-member, means for oscillating the latter to engage and disengage the contacts for making and breaking the circuit through the cell and bulb, and means extending outwardly through the cap, providing for the operation of the switch-mem- 65

ber and the suspension of the lamp-structure as a unit.

5. A portable electric hand-lamp, having a casing, a cap therefor, an electro-chemical cell in the casing, a lamp-bulb in the cap, an insulating-ring in the cap, a plate-like oscillatable disk-shaped switch-member located in a plane transverse to the axis of the lamp-structure, interposed between the inner edge of the said ring and the outer end of the said casing and frictionally gripped between the same with variable restraint as to its oscillatable movement, contacts carried by the ring and switch-member, and means projecting outwardly through the cap for oscillating the switch-member to make and break the circuit through the cell and lamp-bulb. 70 75 80

6. A portable electric hand-lamp, having a casing, a cap therefor, an electro-chemical cell in the casing, a conical reflector having a threaded sleeve-socket located in the cap, a lamp-bulb having a threaded stem installed in the socket of the reflector, an insulating-ring located in the cap and receiving the reflector, a plate-like oscillatable switch-member frictionally interposed between the said ring and casing and having means to prevent the reflector and lamp from undue canting when the lamp is being assembled, contacts carried by the said ring and switch-member, and means projecting outwardly through the cap for oscillating the switch-member to engage and disengage the said contacts for making and breaking the circuit through the cell and lamp-bulb. 85 90 95 100

7. A portable electric hand-lamp, having a casing, a cap therefor, an electro-chemical cell having outward movement in the said casing, a conical reflector having a threaded sleeve-socket located in the said cap, a lamp-bulb having a threaded stem installed in the said socket of the reflector, and a peripherally-mounted plate-like disk-shaped oscillatable switch-member located in the said cap in a plane transverse to the axis of the lamp and having an inwardly-extending concentric guard-cone receiving the said threaded sleeve-socket of the reflector and forming a positive stop for limiting the outward movement of the cell, whereby injury to the lamp-bulb is avoided and the circuit prevented from being accidentally closed by the engagement of the electrode of the cell with the said reflector. 105 110 115 120

In testimony whereof, I have signed this specification.

PAUL R. PUCKETT.
